UNITED STATES PATENT OFFICE.

GEORGE J. STENGEL, OF YONKERS, NEW YORK, ASSIGNOR TO ALEXANDER SMITH & SONS CARPET COMPANY, OF NEW YORK, N. Y., A CORPORATION OF NEW YORK.

DESIGN FOR A RUG.

42,614.

Specification for Design.

Patented June 11, 1912.

Application filed February 21, 1912. Serial No. 679,137. Term of patent 3½ years.

To all whom it may concern:

Be it known that I, GEORGE J. STENGEL, a citizen of the United States, residing at Yonkers, in the county of Westchester and State of New York, have invented a new, original, and ornamental Design for a Rug, of which the following is a specification, reference being had to the accompanying drawing, forming a part thereof.

The figure is a face view of a rug showing the design.

The design is intended to be worked into or upon rugs or similar fabrics in such colors as may be desired.

I claim:

The ornamental design for a rug as shown and described.

GEORGE J. STENGEL.
